(57) **CLAIM**

The ornamental design for a display screen or portion thereof with graphical user interface, as shown and described.

DESCRIPTION

The FIGURE is a front view of a display screen or portion thereof with graphical user interface showing the claimed design.

The outermost broken line rectangle a display screen or portion thereof, and forms no part of the claimed design. All other broken lines illustrate portions of the graphical user interface and form part of the claimed design.

Portions of the FIGURE are illustrated to show contrasting appearance. Areas of the display screen or portion thereof with graphical user interface that appear in different shades of gray represent areas with contrasting appearances.

The display screen or portion thereof with graphical user interface may be, for example, a computer, tablet, or mobile device with display function.

1 Claim, 1 Drawing Sheet

The dashboard displays four data visualizations:

- SUDS Diagnosis Rates By County**: A line chart showing opioid diagnosis rates from 2010 to 2016. The Y-axis ranges from 0 to 7.5. The chart shows a general downward trend across all counties, with some fluctuations. The legend includes [county], [data range], and [opioid rx rate].
- Opioid DX Rate by County**: A bar chart showing opioid diagnosis rates by county. The bars are labeled with placeholder text: "Lorem ipsum dolor sit amet" for the first two bars and "Lorem ipsum" for the last two. The legend includes [Opioid DX Rate] and [County].
- SELECTED - 0**: A map of the United States where states are shaded in a dotted pattern. Specific counties are highlighted in black. The highlighted counties are labeled with placeholder text: "Lorem ipsum County" for the first two and "Lorem ipsum County" for the last two. The legend includes [Opioid DX Rate] and [County].
- ORDINAL**: A scatter plot showing the relationship between patient count and annual spend. The X-axis is labeled "patient count" and ranges from 3 to 8. The Y-axis is labeled "annual spend" and ranges from 3 to 8. The data points are clustered in two main groups: one at lower patient counts and higher annual spend, and another at higher patient counts and lower annual spend. The legend includes [patient count], [Opioid DX Rate], [date], [annual spend], and [member cost].
- GEOGRAPHICAL**: A scatter plot showing the relationship between state and county. The X-axis is labeled "state" and the Y-axis is labeled "county". The data points are scattered across the plot area, with a higher density in the central US. The legend includes [state] and [county].
